PORTABLE COOKING AND ACCESSORY UNIT FOR EDUCATIONAL DEMONSTRATION

Justine Smey, Great Neck, N. Y.

Application May 10, 1951, Serial No. 15,117

Term of patent 14 years

(Cl. D81—10)

To all whom it may concern:

Be it known that I, Justine Smey, a citizen of the United States of America, residing at Great Neck, in the county of Nassau and State of New York, have invented a new, original, and ornamental Design for a Portable Cooking and Accessory Unit for Educational Demonstration, of which the following is a specification, reference being had to the accompanying drawing, forming part thereof.

Fig. 1 is a front perspective view of a portable cooking and accessory unit for educational demonstration in closed position showing my new design;

Fig. 2 is a similar view thereof with the doors in open position; and

Fig. 3 is a front elevational view of the unit in closed position.

The end not shown is substantially plain.

I claim:

The ornamental design for a portable cooking and accessory unit for educational demonstration, as shown and described.

JUSTINE SMEY.
